UNITED STATES PATENT OFFICE.

EDWIN F. BROWN, OF CHICAGO, ILLINOIS.

COLLAR.

SPECIFICATION forming part of Letters Patent No. 709,074, dated September 16, 1902.

Application filed June 5, 1902. Serial No. 110,319. (No model.)

To all whom it may concern:

Be it known that I, EDWIN F. BROWN, a citizen of the United States, residing at Chicago, county of Cook, State of Illinois, have 5 invented a certain new and useful Improvement in Collars; and I declare the following to be a full, clear, and exact description of the invention, such as will enable others skilled in the art to which it pertains to make and use 10 the same, reference being had to the accompanying drawings, which form a part of this specification.

My invention has for its object the production of what is popularly known as a 15 "turn-down" collar, which when a tie is used with it will not spread or open at the meeting edges of the ends of the collar, but will remain in its position notwithstanding the insertion of a tie between the adjacent edges 20 of the ends.

It consists, essentially, in the provision in each of the vertical edges of the outer fold of the collar of a notch or recess, so that when the ends are brought together on the neck of 25 the wearer there is a comparatively circular opening or space in which the knot of the bow-tie may rest, thus preventing the bulging out of the outer fold of the collar, thereby throwing the parts out of their normal position.

In the drawings, Figure 1 is a perspective view of my collar, and Fig. 2 a perspective view showing the tie in place.

In carrying out the invention, A represents the outer fold or portion of the collar, the 35 ends of the inner fold or portion being shown by the dotted lines aa' . In each of the vertical edges of the outer fold is a recess a^2 , the two recesses being opposed to each other, so that when the collar is brought together on the 40 neck of the wearer a substantially circular opening in the outer fold is made to receive the knot B of the tie. By the provision of the opening just described the knot is prevented from bulging the outer fold out of 45 place, thereby preventing the spreading of the ends of the meeting edges, as would be the case if the outer fold did not lie flat and in its normal position. The above-described openings also prevent the tie from moving 50 out of place, either up or down or in any other direction.

What I claim is—

1. In a turn-down collar the outer fold thereof provided in its end with a recess to 55 receive the knot of the tie.
2. In a turn-down collar the outer fold thereof provided in each end with a recess to receive the knot of the tie.

In testimony whereof I sign this specification in the presence of two witnesses.

EDWIN F. BROWN.
